UNITED STATES PATENT OFFICE.

HARRY W. BUSLER, OF LITTLETON, NEW HAMPSHIRE.

SHARPENING-MACHINE FOR EDGE-TOOLS.

1,139,485.

Specification of Letters Patent. Patented May 18, 1915.

Application filed December 14, 1914. Serial No. 877,175.

To all whom it may concern:

Be it known that I, HARRY W. BUSLER, a citizen of the United States, residing at Littleton, in the county of Grafton, State of New Hampshire, have invented certain new and useful Improvements in Sharpening-Machines for Edge-Tools, of which the following is a description, reference being had to the accompanying drawings, forming a part hereof.

My invention relates to machines for sharpening edge tools, and particularly to machines for sharpening razor blades, knife blades and other cutting instruments in which the blade or cutting portion of the tool is sharpened by abrading or grinding both faces of its edge.

My invention has for its object to provide a machine for such purpose which will be adapted to automatically grind, hone and burnish the blade or other tool by relatively coarse and fine grinding rolls and to finish the edge by stropping rolls.

My invention has for a further object the provision of means by which the blade or other tool is held against lateral movement during the operation of the grinding, honing, burnishing and stropping rolls and the rolls brought against opposite faces to form a sharp edge.

My invention has for a further object the provision of means by which the grinding, honing and burnishing rolls are operated in one direction relative to the blade or other tool being sharpened and the stropping rolls are operated in the opposite direction relative to such blade or tool.

My invention has for a further object to provide means by which the blade or other tool to be sharpened is conveyed through the machine automatically, or otherwise, so as to be placed in position to be first operated on by the grinding rolls and then to be moved into position to be operated on by the stropping rolls.

My invention has for a further object to provide means for conveying the blade or other instrument to be sharpened so that it will be held against longitudinal movement during the operation of the grinding rolls and then moved longitudinally into position to be operated on by other rolls and then held against longitudinal movement during the operation of such other rolls.

My invention has for a further object to provide an arrangement of grinding rolls

of differing character and stropping rolls in connection with means for conveying the blade or tool through the machine by which such blade or tool in a single passage through the machine may be given the fine edge required for a satisfactory razor blade.

My invention has for a further object to provide improved means for effecting the movement of the sharpening rolls from opposite sides toward the blade or other tool to be sharpened.

With these and other objects hereinafter explained in view my invention consists in the construction and combination of elements hereinafter described and particularly pointed out in the claims.

Referring to the drawings, Figure 1 is a front view in elevation of a machine embodying my invention. Fig. 2 is a rear view in elevation of the same machine. Fig. 3 is an end elevation looking toward the right of Fig. 1. Fig. 4 is an end view looking toward the left of Fig. 1. Fig. 5 is a cross sectional view on an enlarged scale on line 5-5 of Fig. 2. Fig. 6 is a horizontal sectional view of the mechanism shown in Fig. 5 on line 6-6 of that figure. Fig. 7 is a detail perspective view of the carrier for the blade or other tool to be sharpened.

Referring to the drawings which illustrate a machine particularly adapted for sharpening or resharpening blades of safety razors, 1 indicates the base of the machine, which is supported by legs 2, to which is secured, below the base of the machine, a frame 3 which serves to hold the legs rigid and to support the bearings 4 in which is carried the driving shaft 6.

The driving shaft 6 is provided at one end with fast and loose pulleys 7 and 8 adapted to receive a belt from a shop shaft or other suitable source of power. A belt shifter 9, arranged to be operated by a hand lever 10, serves to shift the driving belt from the loose to the fast pulley to start the machine, or from the fast to the loose pulley to stop the machine.

Near the fast and loose pulleys the driving shaft is provided with grooved pulleys 11 and 12 of relatively large diameter, and near its other end the shaft is provided with grooved pulleys 13 and 14, also of relatively large diameter, and near its end the shaft is provided with pulley 15, of relatively small diameter, the pulleys 11 and 12 carrying belts for driving the shafts for rotating the

grinding rolls, and the pulley 15 carrying a belt for driving the shaft through which the grinding rolls and the stropping rolls are moved toward and from the blade or other tool to be sharpened.

5 The machine base 1 is provided at its ends with standards 16 and 17 shaped somewhat like an inverted U, and between its ends is a similar standard 18. These standards are arranged in line and extend over the sharpening rolls and support the means for carrying the blade or other tool to be sharpened through the machine. These standards are connected by longitudinal rods 19, 20 at their bases and rod 21 at their tops.

10 Between their legs are arranged the pairs of grinding rolls 22 and the pairs of stropping rolls 23. The grinding and honing rolls 22 are preferably made up of sections 22', 22², 22³ and 22⁴ of different degrees of coarseness, the section 22' being preferably 15 of the coarsest and most rapid cutting quality and the other sections being successively of relatively less coarse quality, the section 22⁴ being preferably of such fine quality as to effect a honing rather than a grinding of the blade or other tool which has been ground to a sharp edge by the sections 22', 22² and 22³. The stropping rolls are rolls 20 having their surfaces of leather or canvas or like material adapted to draw the edge to 25 the desired keenness.

The grinding and honing rolls 22 are mounted on shafts 25 in the upper ends of 30 swinging arms 26, the lower ends of which are arranged to swing on longitudinal shafts 27 which are suitably supported, as herein-after described, in the machine base 1. One 35 of swinging arms 26 is connected by links 28 to an arm 29 carried by a longitudinal rock shaft 30 mounted in bearings 31 near the rear edge of the machine base 1. Rock shaft 30 is provided with arm 32, the upper end of which is connected to link 33, the 40 other end of which is connected to an eccentric pin 34 on a disk 35 which is adjustably secured to a disk 36 on the end of a shaft 37 journaled in bearings 38 on the rear edge of standards 16 and 18.

45 To the inner ends of the heads of the swinging arms 26 are secured depending arms 39, and between the lower ends of these depending arms is arranged a screw 40 carrying nuts 41 on each side of each of the depending arms 39. By means of these nuts the distance between the sharpening rolls may be adjusted. The rotation of shaft 37 through the eccentric pin 34 causes the arms 26 to swing to and fro, swinging the grinding rolls 22 toward and from the blade or other tool on which they are to act.

50 The stropping rolls 23 are mounted on shafts 25', which are journaled in bearings 55 in the upper ends of swinging arms 26' 55 which are arranged to swing on shafts 27'

and are arranged to be swung to and fro by link 28' connected at its outer end to the upper end of arm 29' on rock shaft 30.

The shafts 25 of the grinding rolls are provided on their outer ends with pulleys 70 42 and the shafts 25' of the stropping rolls are provided on their outer ends with pulleys 45. The pulleys 42 are driven by belts 46 from pulleys 13 and 14 on the driving shaft, the forward belt 46 being crossed and 75 the rear belt being straight, so that the two grinding rolls will be rotated, as indicated by arrows in Fig. 3, to cause their surfaces to cut away the edge of the blade in a direction away from the edge. The pulleys 45 are driven by belts 47 from pulleys 11 and 12 and the rear belt is crossed while the forward belt is straight, so that the stropping rolls are rotated, as indicated by arrows in 80 Fig. 4, in directions to cause their surfaces to act toward the edge of the blade.

In the upper part of each of the standards 16, 17 and 18, directly above the rolls 22 and 23, are secured two parallel flat track bars 48 and 49, spaced apart on a central line 90 directly above the space between the grinding and stropping rolls. Above these bars 48 and 49 are arranged similar track bars 50 and 51, spaced a short distance above the track bars 48 and 49 and also spaced apart 95 from each other, the four track bars 48, 49, 50 and 51 being so arranged that they are adapted to receive and guide in the spaces between them the horizontal arms 52, 53 and the vertical arms 54, 55 of a cruciform carrier in which the tool to be sharpened is carried and which is here shown as adapted to carry a safety razor blade. For this purpose the lower vertical arm 55 is provided at 100 its lower end with a longitudinal slit 56 adapted to receive a safety razor blade and also provided with holes 57, 58, through the walls of the slot to receive bolts 59 carrying thumb nuts 60, by which the walls of the slit 56 may be drawn together to clamp 105 the razor blade to hold it with its edge in position to be acted on by the sharpening rolls.

The carrier is moved between the track bars by sprocket chains 61 and 62. These 115 sprocket chains are endless chains and are carried respectively by sprockets 63 and 64, one at each end of the machine and sprockets 65 and 66, also one at each end of the machine. These sprocket wheels 63 and 65 120 at the right hand end of the machine in Fig. 1 are carried on short shafts on which are also carried driving sprocket wheels 67 and 68, somewhat larger in diameter than the sprockets 63 and 65. These sprockets 67 and 68 are connected by sprocket chains with sprockets 70 and 71 on a cross shaft 72 journaled in bearings on the right hand end of the machine base 1.

125 It will be seen that by the arrangement 130

just described rotation of the shaft 72 will, through the sprockets 70 and 71, rotate the sprockets 63 and 65 and cause the chains 61 and 62 to travel, carrying with them the carrier and the blade held in its lower end.

The shaft 72 is arranged to be rotated intermittently so as to feed the blade to be sharpened forward into position to be acted on by the first section of the grinding rolls and allow it to stop there while the rolls act on it, and to then move it forward into position to be acted on by the next section of grinding rolls and allow it to stop there while it is further acted on and then again move it forward and stop, and so on until all of the sections of the grinding rolls and the stropping rolls have acted to sharpen the blade and bring its edge to the fineness desired.

In order to swing the sharpening rolls to and fro and to effect the feeding forward of the blade to be sharpened the shaft 37 is provided on its outer end at the right of the machine, as shown in Fig. 1, with a pulley 75 of relatively larger diameter, which is connected by a belt with the small pulley 15. On the shaft 37 near the pulley 75 is a cam 76. On the end of cross shaft 72 is secured a ratchet wheel 77, the teeth of which are engaged by a dog 78 pivoted on a lever 79 arranged to swing on the shaft 72 and extending upward and downward from the shaft. At its upper end this lever 79 is provided with a roller 80 arranged to be engaged by the cam 76 as the shaft 37 is rotated. The lower end of the lever 79 is connected by a spring 81 with the frame of the machine. As the shaft 37 rotates it will, through the eccentric pin 34, cause the sharpening wheels to swing to and fro, bringing one of them against one side of the edge of the blade and then bringing the other roll against the other side of the blade. Also as the shaft 37 rotates the cam 76 will act against the roller 80 to cause the lever 79 to swing toward the right of the machine, as shown in Fig. 2 and, through the action of the dog 78 on the ratchet wheel 77, causing the shaft 72 to rotate to effect the feeding forward of the carrier, as above described. As the rotation of shaft 37 continues the cam 76 will pass by the roller 80 and the lever 79 will then be returned to its initial position by spring 81. As soon as the cam passes by the roller 80 the rotation of shaft 72 stops and of course the movement of the feed chains stops and the carrier remains stationary, holding the blade to be sharpened stationary to be acted on by the sharpening rolls between which it is located at the moment.

In order to provide for raising or lowering the sharpening rolls and adjusting them laterally, the shafts 27 and 27' are carried by plates 82 which have openings at their

centers to receive the ends of the shafts. At its ends each of these plates is provided with open ended slots 83. These plates are held against the standards 16, 17 and 18 by cap screws 84, which are of a diameter less than the width or length of the slots 83 and washers 85. By reason of the screws being of less diameter than the width or length of the slots the plates may be adjusted vertically and horizontally so as to adjust the position of the shafts 27 and 27' and thus adjust the position of the sharpening rolls, the permitted adjustment not being, however, enough to shift the position of the pulleys 42 and 45 enough to interfere with the driving of these pulleys by the belts 46 and 47.

In operation the sharpening rolls being adapted to proper position, a razor blade is secured in the slit 56 of a carrier and the carrier is inserted in the machine at the right of the machine, as shown in Fig. 1, with the horizontal arms 52 and 53 between the track bars 48 and 50 and 49 and 51, and with its upper vertical arm 54 between the track bars 50 and 51 and its lower vertical arm between the track bars 48 and 49. The blade to be sharpened is thus held rigidly against any lateral movement. The machine being then started, the cam 76 acting against roller 80 on lever 79, causes the feed chains to move forward, carrying with them the carrier and placing the blade to be sharpened between the sections 22' of the grinding rolls, where it stops. The rotation of the shaft 37, through the eccentric pin 34, causes the pair of rolls 22 to swing first in one direction and then in the other to bring the grinding surface to first one roll and then the other against the sides of the edge of the blade to grind it away, the grinding rolls being rotated at a rapid speed relatively to the speed of rotation of the shaft by which the to and fro swing is effected, the rolls being driven by relatively large pulleys on the driving shaft and relatively small pulleys on the shafts of the rolls, and the shaft 34 being driven by a relatively small pulley on the driving shaft and a relatively large pulley on the shaft itself.

The eccentric pin is so adjusted that after causing first one and then the other grinding roll to be brought into contact with the blade to be sharpened, it will cause the arms 26 and 26' to swing into vertical position so that neither of them will be in contact with the blade. As the arms 26 and 26' reach this position, the shaft 37 completing a rotation, causes the cam 76 to again act on the roller 80 to swing lever 79 and cause the feed chains to advance the carrier and bring the blade into position between sections 22' of the grinding rolls and leave it there as the cam passes the roller 80. The grinding rolls are then swung as before to bring first one and then the other of sections 22' into con-

tact with the blade to further grind it away to a somewhat less degree, owing to the finer quality of the grit of sections 22² than was done by sections 22'. This operation will be 5 repeated as before until the blade has been acted on successively by the sections 22', 22², 22³ and 22⁴ to effect the coarse grinding and the honing and burnishing, and the blade will then be moved forward between the 10 stropping rolls, which will give the blade fine edge needed for use as a razor blade.

While only one carrier has been shown, it should be understood that a number of them may be used, so that one razor blade may be 15 between the grinding rolls and another between the stropping rolls, or even, if a number of carriers are used, one blade may be between each pair of sections of the grinding rolls and four or more blades may be 20 between the stropping rolls at the same time.

For the purpose of changing the speed of shaft 37, the driving shaft may be provided with a pulley 15' and the shaft 37 with a pulley 75', so that by shifting the driving 25 belt from pulleys 15 and 75 to 15' and 75' the shaft 37 will be driven at a higher speed, as will be readily understood.

It should be understood that the term "sharpening rolls" as used in the description 30 and in the claims is to be understood as including the grinding, honing and burnishing rolls and also the stropping rolls, and the term "grinding rolls" is to be understood as including the several sections 22', 22², 22³ and 22⁴, though in practice the sections 22² and 22⁴ should be formed of very fine grit, corresponding to or even finer than that of which the ordinary razor is made, so that section 22³ will hone rather than grind 40 and section 22⁴ will burnish rather than grind or even hone.

It will, of course, be understood that I do not desire to be limited to the precise construction or arrangement herein described 45 and shown, as it is obvious that the details of the construction and arrangement may be varied without departing from the spirit of the invention.

Having thus described my invention, 50 what I claim is:

1. In a sharpening machine for edge tools a sharpening roll arranged to be movable transversely to its axis, a carrier movable on a line parallel with the axis of the sharpening roll adapted to hold the tool to be sharpened, means for moving the sharpening roll into and out of contact with the tool held in the carrier, and means for moving the carrier timed to operate as the sharpening roll is moved out of contact with the tool in the carrier.

2. In a sharpening machine for edge tools a sharpening roll arranged to be movable transversely to its axis and formed of sec-

tions of different abrasive quality, a carrier 65 movable on a line parallel with the axis of the sharpening roll adapted to hold the tool to be sharpened, means for moving the sharpening roll into and out of contact with the tool held in the carrier, and means for advancing the carrier from a point opposite one section of the sharpening roll to a point opposite another section arranged to operate as the sharpening roll is moved out of contact with the tool in the carrier.

3. In a machine for sharpening edge tools parallel sharpening rolls arranged in pairs with a space between them movable transversely to their axes, a carrier movable longitudinally of the sharpening rolls adapted 80 to hold the tool to be sharpened in the space between the rolls constituting a pair, means for moving the sharpening rolls transversely to their axes to bring them into and out of contact with the tool in the carrier 85 and means for moving the carrier timed to operate as the sharpening rolls are moved out of contact with the tool in the carrier.

4. In a machine for sharpening edge tools parallel sharpening rolls arranged in pairs 90 having a space between them, the sharpening rolls comprising grinding rolls and stropping rolls, a carrier movable longitudinally of the sharpening rolls adapted to hold the tool to be sharpened on a line between the pairs of rolls, means for moving the sharpening rolls into contact with the tool to be sharpened and means for moving the carrier from the grinding rolls to the stropping rolls.

5. In a machine for sharpening edge tools parallel sharpening rolls arranged in pairs having a space between them, the sharpening rolls comprising grinding rolls and stropping rolls, a carrier movable longitudinally of the sharpening rolls adapted to hold the tool to be sharpened on a line between the pairs of rolls, means for moving the sharpening rolls into contact with the tool to be sharpened, means for moving the carrier from the grinding rolls to the stropping rolls, means for rotating the grinding rolls in one direction, and means for rotating the stropping rolls in the other direction.

6. In a machine for sharpening edge tools parallel sharpening rolls arranged in pairs with a space between them, the rolls constituting a pair being simultaneously movable transversely of their axes, a carrier movable longitudinally of the sharpening rolls adapted to hold the tool to be sharpened in the space between the rolls constituting a pair, and means for moving the rolls constituting a pair to and fro to bring first one 120 and then the other into contact with the tool held in the carrier.

7. In a machine for sharpening edge tools

parallel sharpening rolls arranged in pairs with a space between them, the rolls constituting a pair being simultaneously movable transversely of their axes, a carrier movable longitudinally of the sharpening rolls adapted to hold the tool to be sharpened in the space between the rolls constituting a pair, means for moving the rolls constituting a pair to and fro to bring first one and then the other into contact with the tool held in the carrier, and means for moving the carrier timed to operate as the rolls are in position in which neither is in contact with the tool in the carrier.

15 8. In a machine for sharpening edge tools a pair of parallel sharpening rolls spaced apart and arranged to be simultaneously movable transversely to their axes, means for adjusting the space between the rolls, a carrier movable longitudinally of the rolls adapted to hold the tool to be sharpened in the space between the rolls, and means for moving the rolls transversely to their axes

to bring first one and then the other into contact with the tool held in the carrier. 25

9. In a machine for sharpening edge tools a pair of parallel sharpening rolls spaced apart and arranged to be simultaneously movable transversely to their axes, means for adjusting the space between the rolls, 30 means for adjusting the rolls in a direction at right angles to their direction of movement, a carrier movable longitudinally of the rolls adapted to hold the tool to be sharpened in the space between the rolls, 35 and means for moving the rolls transversely to their axes to bring first one and then the other into contact with the tool held in the carrier.

This specification signed and witnessed 40
this 5th day of Sept., A. D. 1914.
